EDGAR A. JONES AND JULIUS A. BIDWELL, OF STURGIS, MICHIGAN.

Letters Patent No. 83,971, dated November 10, 1868.

IMPROVEMENT IN VALVES FOR MELODEONS.

The Schedule referred to in these Letters Patent and making part of the same.

To all whom it may concern:

Be it known that we, EDGAR A. JONES and JULIUS A. BIDWELL, of Sturgis, in the county of St. Joseph, and State of Michigan, have invented a new and useful Improvement in the Valves of Melodeons or other reed-instruments; and we do hereby declare that the following is a full and exact description thereof, reference being had to the accompanying drawings, and to the letters of reference marked thereon.

The nature of our invention consists in providing the spring which keeps the valve to its seat with an intermediate wedge-shaped bearer, slotted on its upper edge, where it bears upon the valve, for the insertion of a staple, whereby its seat is better retained, and lateral play prevented when bearing upon the transversely-grooved recess upon the lower portion of the valve, as will be more fully explained.

Our invention further consists in securing the rear portion of the valve-spring (which is peculiarly formed, as will be particularly set forth,) to its seat by a screw, so as thereby to adjust its pressure upon the valve through the bearer, thus making the touch heavier or lighter by regulating the screw.

In the drawings,

Figure 1 is a perspective view, in which the valve and its seat are shown in an inverted position, for the purpose of more clearly representing our invention.

To the valve-seat B, the valve A is firmly pressed by the spring D coiled around the regulating-screw E, said coil being sufficiently large to permit the necessary play of the spring. The forward part of the spring rests in a circular recess, k, made in the lower part of the wedge-shaped intermediate bearer C, which is slotted in its upper portion to receive the bent wire or staple h. The staple h is fastened to the lower side of the valve A.

The lower portion of the valve A has a transverse groove or recess, as shown at g, in which is seated the upper part of the bearer C, more securely kept to its place by the staple h.

F represents the guide or standard projection or pin, which is placed at the forward end of the valve-seat B, and which serves to keep the valves in position.

Figure 2 is a sectional view of the intermediate bearer C.

By our invention, the friction, caused by the pressure of the spring in the longitudinal recesses in the lower side of the valve, as in one form in ordinary use, or the friction, and, consequently, retarding motion occasioned by the sliding of the slotted backward end of the valve against the pin or projection against which it plays, in another form in common use, is prevented. A firm and uniform pressure upon the valve, causing it to be evenly held to its seat, is also secured.

By the oscillation of the intermediate piece or bearer C, the movement of the valve is much more prompt and free, friction being avoided, and lightness of touch to a greater degree attained.

The adjustment of the spring circularly, instead of at right angles, prevents the liability to breakage consequent upon bending in one place whenever the valve is moved, and at the same time, it being secured to the screw E, renders the regulation of the pressure upon the valve certain and convenient.

What we claim as new, and desire to secure by Letters Patent, is—

1. The bearer C, constructed as described, with its lower edge slotted to fit over and play upon the staple h in the under side of the valve, whereby the lateral movement of the bearer is prevented as herein described, for the purpose specified.

2. The spring D, when formed as described, together with the regulating-screw E, when employed for the purposes and uses set forth.

EDGAR A. JONES.
JULIUS A. BIDWELL.
